US00D602450S

(12) **United States Design Patent**
Edmond et al.

(10) **Patent No.:** **US D602,450 S**
(b4) **Date of Patent:** **** Oct. 20, 2009**

(54) **LED CHIP**

(75) Inventors: **John Edmond**, Cary, NC (US); **James Ibbetson**, Santa Barbara, CA (US); **Michael John Bergmann**, Chapel Hill, NC (US); **Amber Christine Salter**, Durham, NC (US); **David Todd Emerson**, Chapel Hill, NC (US); **Ashay Chitnis**, Goleta, CA (US); **Bernd P. Keller**, Santa Barbara, CA (US); **Kevin Haberer**, Cary, NC (US)

(73) Assignee: **Cree, Inc.**, Durham, NC (US)

(**) Term: **14 Years**

(21) Appl. No.: **29/327,786**

(22) Filed: **Nov. 13, 2008**

(57) **CLAIM**

The ornamental design for an LED chip, as shown and described.

DESCRIPTION

FIG. 1 is a top perspective view of a first embodiment of the LED chip showing our design;

FIG. 2 is a top view thereof;

FIG. 3 is a first side view thereof;

FIG. 4 is a bottom view thereof;

FIG. 5 is a different side view thereof;

FIG. 6 is an end view thereof; and

FIG. 7 is an opposing end view thereof.

FIG. 8 is a top perspective view of a second embodiment of the LED chip showing our design;

FIG. 9 is a top view thereof;

FIG. 10 is a first side view thereof;

FIG. 11 is a bottom view thereof;

FIG. 12 is a different side view thereof;

FIG. 13 is an end view thereof; and

FIG. 14 is an opposing end view thereof.

The broken lines showing portions of the LED chip is for illustrative purposes only and form no part of the claimed design.

1 Claim, 4 Drawing Sheets
